UNITED STATES PATENT OFFICE.

CLIFTON W. NIXON, OF NEW YORK, N. Y.

VENDING MACHINE.

Original application filed July 27, 1922, Serial No. 577,822. Divided and this application filed June 5, 1924. Serial No. 718,163.

The improvements of the present invention have been especially designed by me for use with coin-controlled vending and change-making machines of the type constituting 5 the subject matter of the application for patent filed by me on July 27, 1922, Serial No. 577,822, of which the present application is a division. While my present improvements will be herein disclosed, by way of 10 example, as applied to my coin-controlled vending and change-making machine, it will be recognized that the improvements are capable of embodiment in machines of other types and perhaps in other relations where 15 it is desirable to prevent the playing of the machine for articles not in stock while freely allowing the operation of the machine for articles in stock.

My invention relates to improvements in 20 machines which are dependent for their operation upon the insertion of a coin or coins, and a main object of the same is to provide efficient means whereby automatically to close a coin-deposit slot against the 25 insertion of a coin and thereby to prevent the operation of the machine whenever a stack or compartment of the machine has been exhausted of its supply of merchandise.

Another object of my invention is to provide 30 improvements of this character for use in connection with a machine having a plurality of merchandise-holding stacks or compartments and having two or more coin-deposit slots, whereby automatically first to close and then to open each coin-deposit slot each time an empty stack or compartment is moved into and out of delivery position, so that each of the coin-deposit slots may be open at all times to receive coins for the 40 purchase of articles contained in the non-exhausted stacks or compartments.

For a full understanding of the invention, reference is to be had to the following description taken in connection with the accompanying 45 drawings, which form a part of this application, and in which:

Figure 1 is a vertical cross-section of my machine showing the arrangement and construction of its interior mechanisms including in particular a unit of the slot closing means.

Fig. 2 is a partial sectional view, showing at a delivery station the relation of the lower portion of a merchandise-holding 55 stack to the slot closing means.

Fig. 3 is a front view of the same parts, but with the merchandise-holding stack exhausted of its contents and the slot closing means actuated to close the coin-deposit slot.

Fig. 4 is a partial sectional view from the rear or from the interior of the machine, showing the gate for closing the coin-deposit slot.

Fig. 5 is a face view of the machine, with parts broken away, showing units of the slot closing means in connection with stack groups at the delivery stations.

In the accompanying drawings, I have illustrated my improvements in connection with several features of my coin-controlled vending and change-making machine which constitutes the subject matter of the aforementioned application filed on July 27, 1922. This machine has a casing or cabinet 7 within which is mounted a rotary magazine consisting of top and bottom ring-plates 8 and 9 connected by equi-spaced vertically extending merchandise-holding stacks 10. With each of the merchandise stacks is associated a bank comprising a set of coin-holding stacks 11, 12 and 13 for holding change of different denominations, each merchandise stack with its set of coin stacks constituting a stack group or unit of the machine. 85 Arranged for reciprocating movement upon the bottom ring-plate 9 radially inward of each stack of each group is a structurally independent spring retracted ejector device 14 by which the articles contained within 90 the stack are ejected at the delivery stations. For each stack, therefore, there is an individual ejector device; and the ejector devices for each stack group are acted upon differentially at the different delivery stations of the machine in order to deliver to 95 the customer along with the article purchased the correct change, if any change be due him.

In Fig. 5 the delivery stations are indicated by the observation windows 15, 16 and 17, so spaced that the merchandise stacks will come into radial agreement therewith under the stepping of the magazine. Directly above the windows are the coin-deposit slots 18, 19 and 20, for the respective stations, these slots differing in size in order to accommodate different sizes or denominations of coins. Within the casing (Fig. 1) in communication with the slot 19 is a coin-

deposit chute 21 which delivers the deposited coin between the co-operating heads 22 and 23 carried by the respective reciprocating levers 24 and 25. The deposited coin forms a connection between said levers so that the second lever 25 may be actuated by the thrusting of the first lever 24 accomplished through the exterior push button 26, located at the station corresponding to the window 16 and the coin-deposit slot 19. The movement of the second lever 25 is imparted through the elements 27, 28, 29 and 30 to a master-pusher 31 located inside the circle of ejectors at the station corresponding to the window 16. This master-pusher operates a predetermined number of ejectors for each stack group that is stepped to the delivery window 16. For each of the other coin-deposit slots 18 and 20 there is a similar coin-controlling mechanism (not shown) within the casing for operating a master-pusher behind the respective station windows 15 and 17. Under this arrangement merchandise and change may be delivered from each of the stack groups at each of the station windows 15, 16 and 17.

For the purpose of stepping the magazine to bring the stack groups successively behind the station windows, the top ring-plate 8 is provided with a series of upturned teeth 32, of which there is one for each stack group. Adapted to engage these teeth successively is a draw-bar 33, pivoted axially of the magazine on a stud 34 provided on the horizontal frame part 35. The draw-bar is constantly urged forward by a pull spring 36 against the urge of which it is thrust over the next succeeding ring-plate tooth by means of a push rod 37 carrying exteriorly of the casing a push button 38. Momentarily prior to each engagement over a tooth 32, the draw-bar engages a contact plate 39 for the purpose of withdrawing a locking bar 40, thereby freeing the magazine for its step movement. All of these mechanisms are described in detail in my aforementioned application.

Whenever all of the merchandise has been ejected from any one of the merchandise stacks it is necessary by positive means at each station to prevent the customer from depositing his coins and playing or operating the machine for merchandise in the empty stack. Further, it is necessary to accomplish this result without interfering with the operation of the machine at any station for the purchase of merchandise from the stacks which have not been exhausted of their supply of articles. To these ends I provide for each merchandise stack a weight 41 furnished with a centrally depending pin 42. Each weight is so made that it will have slidable fit within the stack for which it is intended, and it is so inserted in its stack that its pin will rest upon the

topmost article therewithin. The bottom ring-plate 9 at the center of each merchandise stack is provided with an aperture 43 through which the pin will be projected when the weight drops after the ejection 70 from the stack of the last article 44 of merchandise.

Located upon a cross partition 45 under the bottom ring-plate 9 at each of the delivery stations is a bracket 46 which pivotally supports a rock-lever or treadle 47. These rock-levers are so positioned that their free flat ends 48 will be engaged and depressed by the weighted pins when the latter drop through the apertures 43. The opposite or forward ends of the rock-levers are formed with laterally extending arms 49 furnished with upstanding lugs 50 with which are pivotally engaged the lower ends of the connecting rods 51. Each of the rods 51 extends upwardly of the casing and has its upper end pivotally engaged with a lug 52 formed at the free end of a lever 53. As exemplified in Fig. 4, each lever 53 is made in the form of a bell crank, having an angular neck portion 54 which merges into a forwardly offset closure gate or blade 55, adapted to bar the insertion of a coin into the coin-deposit chute through the adjacent coin-deposit slot. Thus, for instance, when the rock-lever 47 at the station window 16 (Fig. 5) has been depressed no coin can be inserted through slot 19, for the gate 55 will have moved into the position shown by the broken lines in Fig. 4, completely barring the entrance to the coin-deposit chute 21. In a similar manner, when the rock-levers for the delivery stations at the windows 15 and 17 are depressed, the coin-deposit slots 18 and 20, corresponding thereto respectively, will be closed against the insertion of coins.

Each gate is pivoted as at 56 to the inner-side of the casing flatwise thereof, and its lever 53 is made heavy to constitute a weight so that immediately the pin 42 slips off the rock-lever when the magazine is stepped around, the gate will swing by gravity into open position and the rock-lever will in consequence of this movement be repositioned for the next operation.

According to another feature of my improvements, I secure upon the horizontal partition 45 at each delivery station in juxtaposition to each rock-lever on the side of the magazine's approach thereto, a riser 57 having an upward inclination 58 leading to a ledge 59. Each riser has its upward inclination facing the direction of the approach of the downwardly projecting pin and has its ledge partly projecting over the flat portion 48 of the adjacent rock-lever, so that as the magazine is stepped around, the pin depending from the empty stack will ride up the riser and onto the ledge and then

drop precipitately upon the rock-lever, thereby closing the gate for the coin-deposit slot corresponding to that station just as the empty stack moves into delivery position at the station. Every time, therefore, an empty stack comes into each delivery station, the corresponding coin-deposit slot will be closed, so that the customer cannot place his money against articles that are not available. Inasmuch as each gate is opened by force of gravity as soon as the projecting pin is drawn off the rock-lever under the movement of the magazine, the coin-deposit slots are always open for the customer to place his money on the stacks that contain a supply of articles.

While I have thus described and illustrated my preferred mechanism for automatically closing and opening the coin-deposit slots, it will be understood that changes and alterations in the details of construction may be made therein, to which changes and alterations I am entitled, provided the same are effected within the scope of the annexed claims.

Having thus described my invention, what I claim is:

1. In a vending machine, a casing provided with a coin-deposit slot, a movable magazine provided with a merchandise stack, a weighted-pin arranged in the stack to be projected therefrom when there are no articles in the stack, means for closing the coin-deposit slot including a pivoted lever arranged to receive said weighted-pin, and means for riding said weighted-pin upwardly into position to be received by said pivoted lever.

2. In a vending machine, a casing provided with a coin-deposit slot, a movable magazine provided with a merchandise stack, a movable member in the stack arranged to be projected therefrom when there are no articles in the stack, means for closing the coin-deposit slot including a treadle device arranged to receive the movable member thereon, and a riser device for raising up the movable member and dropping it onto said treadle device as the magazine turns.

3. In a vending machine, a casing provided with a plurality of coin-deposit slots, a movable magazine therein provided with a plurality of merchandise stacks, a gravity controlled member associated with each stack and arranged to protrude therefrom when it drops consequent upon the removal of all the articles from the stack, independently operated means for closing each coin-deposit slot including a treadle device arranged to receive and to be operated by the force of the drop of the gravity members, and a riser device positioned in advance of each treadle device for raising each gravity member and dropping it onto the treadle device as the magazine turns, whereby to

effect the closing of each coin-deposit slot independently of the closing of the other of the coin-deposit slots.

4. In a vending machine, a casing provided with a coin-deposit slot, a gate adapted to close said slot, a movable magazine in the casing provided with a merchandise stack, a weighted-pin associated with the stack and adapted to be protruded upon the ejection of all the articles from the stack, a treadle device arranged to receive the weighted-pin and to be operated thereby, means for causing the weighted-pin to rise into position to drop upon the treadle device, and an operative connection between said treadle device and said gate.

5. In a vending machine, a casing provided with a coin-deposit slot and a gate adapted to close said slot, said gate being normally held open by gravity, a movable magazine in the casing provided with a merchandise stack, a movable gravity operated member depending from said stack, a treadle device link-connected with said gate and set in position for operation by the gravitational force thereof, said treadle device being arranged to receive the gravity operated member and to be operated by the force of the fall thereof, and means for causing the gravity operated member to rise to position to fall upon said treadle device.

6. In a vending machine, a casing provided with a plurality of coin-deposit slots and a gate adapted to close each slot, a magazine rotatably disposed within the casing and provided with a plurality of stacks adapted to hold articles, ejecting stations corresponding in number to the number of gates, a weighted-pin associated with each stack and adapted to be protruded upon the ejection of all the articles from the stack, a treadle device at each ejecting station, link-connected with each corresponding gate and adapted to be operated by the fall of the weighted-pins thereon, and riser means at each ejecting station arranged to cause the weighted pins to rise as the magazine turns so that they can fall upon the treadle devices.

7. In a vending machine, the combination with a casing having a coin-deposit slot and a gate to close said slot, of a magazine rotatably mounted within the casing and constructed with a stack from which articles may be ejected, said stack having an apertured bottom, a movable member in said stack arranged to be projected through said apertured bottom when there are no articles in said stack, a rock-lever arranged to receive said movable member and to be depressed thereby, means operable by the depression of said rock-lever for closing said gate, and riser means for causing said movable member to rise so that it can drop upon said rock-lever.

8. In a vending machine, a casing provided with a coin-deposit slot and a gate adapted to close said slot, a magazine rotatably disposed within the casing and constructed with a stack from which articles may be ejected, said stack having an apertured bottom, a pin within said stack and weighted to fall by gravity through said apertured bottom when all the articles have
10 been ejected from the stack, a rock-lever to receive said pin and to be depressed thereby,

a riser in advance of said rock-lever and on which said weighted pin will first rise above and then fall onto the rock-lever on each revolution of the magazine, and means connecting said rock-lever with said gate whereby on each depression of the former the latter will be closed.

In testimony whereof, I have signed my name to this specification.

CLIFTON W. NIXON.
